In Canada July 22, 1947

Term of patent 7 years

(Cl. D9—2)

To all whom it may concern:

Be it known that I, Paul Staheli, a citizen of Switzerland, and resident of the city of Montreal, in the Province of Quebec, Dominion of Canada, have invented a new, original, and ornamental Design for a Shoe Cleaning Device, of which the following is a specification, reference being had to the accompanying drawing, forming a part thereof.

In the accompanying drawing:

The figure is a perspective view of a shoe cleaning device, showing my new design.

The side not shown is substantially the same as the one shown.

I claim:

The ornamental design for a shoe cleaning device, as shown and described.

PAUL STAHELI.
